CLAIM

The ornamental design for a toy rifle, as shown and described.

DESCRIPTION

FIG. 1 is a perspective view of the toy rifle embodying the design of the present invention;

FIG. 2 is a side elevational view thereof, the side opposite being a mirror image of the side shown in FIG. 2;

FIG. 3 is an end elevational view thereof;

FIG. 4 is an end elevational view thereof;

FIG. 5 is a top plan view thereof; and,

FIG. 6 is a bottom view thereof.

The rifle is intended to be a toy.

FIG. 1

FIG. 4

FIG. 3

FIG. 5

FIG. 6
